UNITED STATES PATENT OFFICE

LOUIS E. WARD, OF MIDLAND, MICHIGAN, ASSIGNOR TO THE DOW CHEMICAL COMPANY

CURTAIN FOR ELECTROLYTIC CELLS

Application filed July 29, 1929. Serial No. 381,794.

This invention relates in general to a curtain-like means for separating anodic from cathodic products of electrolysis. It relates specifically to a sectional type of curtain 5 adapted for use in separating metallic magnesium and chlorine gas produced by the electrolysis of a fused saline bath containing magnesium chloride.

Owing to the high temperature to which 10 such a curtain is exposed, the corrosive action of chlorine and other anodic products and further to the fluxing or erosive action of the fluid hot metal upon ceramic ware in general, and still further to the necessity that the curtain have electrical non-conductive property, the choice of material for such a curtain is somewhat narrow and the details of construction require careful design. Refractory material such as fire-clay or brick shapes is 15 customarily employed and because such material suffers erosion, corrosion, or breakage it is essential that the details of design shall permit the easy substitution of new parts to replace those no longer serviceable. It may 20 be stated, in general, that such pieces of large size are relatively more expensive than those of small size, are more difficult to pack, ship, unpack, and store without breakage and are more readily broken when handled in a re- 25 placement operation. Small pieces, on the contrary, are more cheaply made, more easily packed and transported, easily stored in small space, and can be handled with a minimum of breakage and loss.

30 I have invented a curtain composed of a plurality of suitably shaped plates of simple design and small size and have invented further means to construct same and means to support said plates in the cell permitting the 35 easy removal and replacement of any single piece even without suspending operation of the cell during such repairs.

To the accomplishment of the foregoing and related ends, the invention, then, consists 40 of the means hereinafter fully described and particularly pointed out in the claims, the annexed drawings and the following description setting forth in detail certain means for carrying out the invention, such disclosed 45 means illustrating, however, but several of

various ways in which the principle of the invention may be used.

In said annexed drawings:—

Fig. 1 is a vertical transverse section of an electrolytic cell employing my invention and 55 adapted to the electrolysis of a fused saline bath for the separation of a metal which will float thereon. Fig. 2 is a vertical longitudinal section through said cell and Fig. 3 is a plan thereof with the cover plates removed 60 to show my improved curtain and other details. Fig. 4 is a transverse section through the form of curtain shown in Figs. 1, 2, and 3. Fig. 5 is a plan of the same curtain assembly and Fig. 6 a side elevation thereof 65 with a portion of the near side broken away to show in cross section a strut hereafter described. Fig. 7 is an end elevation of the said curtain assembly. Fig. 8 is a transverse section of a modified form of curtain. Fig. 70 9 is a plan of such modified form of curtain assembly. Fig. 10 a side elevation thereof, Fig. 11 an end elevation of one member of the curtain assembly, and Fig. 12 a transverse section of a still further modified form of 75 curtain member and assembly. My improved form of curtain comprises an assembly of separate removable refractory members having, in general, a plate-like form, one distinguishing feature being, the method of maintaining opposing members of the assembly in position by means of a strut-like projection or separate member between same.

Referring to Figs. 1, 2, and 3, showing a type of cell to which my improved curtain is 80 adapted, 1 is a cathode cell pot set in a furnace adapted to supply initial or control heat for the bath. A single anode or a plurality 85 2 depend in the bath from above and are preferably set in a straight line between opposing cathode surfaces of the pot. The anodes are further preferably supported by adjustable hangers permitting motion in a vertical direction, removal of anodes from the bath, reinsertion therein and for adjusting the depth 90 of dipping in the bath.

In the type of cell illustrated, the pot is provided with an inverted trough 3, adapted to trap liberated metal rising through the bath from the principal cathode surface 4 95 100

of the pot. Such metal is shown at 5 in the cross hatched areas. The bath level will be approximately as shown in Figs. 1 and 2. Provision may be advisedly made to lead the 5 light metal so entrapped to a collecting well or gathering zone permitting easy access for removing the so-collected metal. Such a collecting well is shown at 12 and the metal collected therein at 13. A second well 14, 10 shown beside 12 in the plan view Fig. 3, is separated from the well 12 by the partition 15 and affords access to the cell for the insertion of a dipper or like utensil by means of which sediment or so called sludge may be 15 dredged from the bath while the cell is in operation. The metal collecting in the well 12 may likewise be dipped or otherwise removed from the cell without interrupting operations. One side 6 of the inverted trough 20 adjacent the collecting well 12 is removed to enable the metal entrapped therein to float out into the collecting well. The removed side is shown in dotted lines as 6 in Fig. 2, which dotted lines also may be taken to represent 25 the unremoved portion thereof adjacent the well 14.

The curtain separating the anodic from the cathodic bath areas is preferably composed of an assembly of refractory plate-like 30 members having surface projections or other equivalent contours enabling the support thereof upon the cell superstructure. Such a curtain is illustrated in longitudinal cross section in Fig. 2 in plan in Fig. 3, and in 35 transverse section in Fig. 1. As seen in the plan Fig. 3 the curtain is composed of two U-shaped end members 7 and two H-shaped intermediate members 8. All such members are provided with a projecting flange resting 40 upon a ledge of the cell superstructure 9. If more or less than three anodes are employed there will be a corresponding increase or decrease in the number of intermediate curtain members 8. The curtain illustrated in Figs. 45 1, 2, and 3, is shown separately in Figs. 4, 5, and 6. Fig. 4 is a cross section on the line AB of Fig. 5 and the partial cross section in Fig. 6 is on the line CD of Fig. 5. The U-shaped member 7 in Fig. 5 is of the same outline 50 as shown in Fig. 3 but a variation thereof is shown at 7' in which two L-shaped members, right and left end, are employed in assembly as the equivalent of the U-shaped members 7, such construction being an alter- 55 native one. Projections 10 may be provided with holes in which will permit the insertion of a tool or other hook shaped device for lifting or otherwise handling the members in the operations hereafter described. The individual curtain members 8 will be seen to be composed of two plate-like portions separated by a strut integral therewith. The strut is shown at 11. The members 8, as well as 7, are carried on their projecting flange by a ledge in the superstructure of the cell and

form together a rectangular inclosure about the anodes separating same from the cathode. The curtain members also blanket the exposed surfaces of the inverted trough 3 restricting cathodic action thereon to a minimum which is highly desirable since metal liberated thereon would not normally enter the trap together with that liberated upon the surface 4.

The cell is further provided with covers 17 75 which inclose an anode gas space 18, served by an outlet 19 adapted to carry away anodic gas products such as chlorine. Covers 20 may be advisedly provided for the collecting well 12 and the dredging well 14.

A further alternative form of curtain member and assembly is shown in Figs. 8, 9, 10 and 11 in which the end members 7 are similar to those heretofore described, while the intermediate members 8 and 8' are T 85 shaped and plate shaped respectively. The stem of the T of one acting as a strut, bearing against the plate form member opposed to the T form member. The construction is readily understood, particularly by referring to the edge view of the member 8 shown in full lines in Fig. 11 and of the member 8' shown in dotted lines therein. A still further modification of an intermediate curtain member such as 8 and 8' is shown in Fig. 12 95 where two similar plate-like members 8'' are separated by a separate strut-like member 8''' resting upon same as indicated in the drawing. The office of the struts shown in the various Figs. is to maintain the opposing members of the curtain assembly in their proper position and space relation.

It will be obvious that other forms of support for the curtain members may be employed, such as pegs or the like, from which the curtain members may be hung, without departing from the spirit of my invention so long as the opposed members of the curtain are separated by strut-like integral or separate members therebetween.

Various other forms of plates and struts may also be employed without departing from the spirit of my invention but sufficient variety has been shown to indicate to one skilled in the art further variations thereof.

When in the course of operation of an electrolytic cell employing curtain members of the type herein disclosed in an assembly such as shown or an equivalent thereof, should one or more members of the assembly become 120 eroded or otherwise unfit for further service it may be replaced with a new member without interrupting the operation of the cell. To do this I provide in a convenient location such new member with its integral strut or without same depending upon the precised detailed, forms employed heated approximately to the temperature of the bath. I then remove one or more of the cover plates 125 17 giving access to the member to be replaced.

I then insert a tool fitted to engage with the member and/or strut to be removed, lift it out of the assembly and then with a similar tool or equivalent replace same with the pre-heated new member previously referred to.

5 The separate strut if employed would then be replaced or a new one inserted if required. The covers may then be replaced and operation again become normal. During the time that the covers are removed sufficient suction will be desirably maintained upon the outlet 19 to avoid the issue of anodic gas into the room. During the operations just described the cell may be continued in operation without loss of output.

10 My invention is applicable to advantageous use in both large and small scale operation. It is particularly applicable in large scale operations employing a plurality of anodes in a large cell. A sectional curtain for such a cell may be readily constructed of small pieces or plates of the character described to form a rectangular, oval, circular, or other enclosure or partition for leading the anodic gas to the outlet, for covering exposed portions of the pot upon which it is desired to restrict cathodic action, and for separating the floating metal from the anodic products.

15 Such a curtain may be constructed far more cheaply and safely than a large sized single piece curtain and renewals will be confined to the replacement of small pieces for any one breakage whereas when large single piece curtains are used, breakage at a single point will require the substitution of a new piece of large size and cost. Not only are small refractory pieces more cheaply made than large ones but they suffer less breakage in drying, burning, packing, shipping, and storage.

20 They require less boxing and packing materials for shipment, less storage room and less labor in handling, are in many respects highly advantageous relative to large sized pieces. I have found the disadvantage incident to the discontinuous character of the curtain, due to the more or less imperfect joint obtainable in actual practice between the adjoining plate edges, to present no serious difficulties in operation. It is customary to employ a suction upon the anodic gas

25 chamber of the cell which effectually prevents issue of the chlorine through the joints in the curtain, and such joints are sufficiently close in practice to substantially prevent metal from passing into the anodic compartment from without. In the form of cell construction illustrated in Fig. 1, the bulk of the metal liberated is trapped as indicated, and but a small portion is liberated upon the surfaces of the metal adjacent to the curtain to become later liable to passage in part through the curtain joints into the anodic gas chamber before removal as metal product.

30 I have described my invention employing refractory material for the curtain plates.

Among materials available are ceramic materials, sintered or fused magnesia, alumina or the like, resistant to the particular bath employed, and I conceive my invention as covering the use of any suitable refractory 70 material for a sectional curtain.

The essence of the invention is the employment of a transverse strut adapted to hold a removable member of a curtain assembly of the character described in place upon a support for such member and I conceive it is within the scope of my invention that such strut may be, as herein disclosed, an integral part of one or more portions or members of the curtain assembly or that it may be a 80 separate and distinct piece adapted to engage with the members to be held in place by it, and I further conceive my invention to cover all equivalent varieties of forms or shapes of the curtain members or the transverse 85 strut employed therewith.

Other modes of applying the principle of my invention may be employed instead of the one explained, change being made as regards the mechanism herein disclosed, provided the 90 means stated by any of the following claims or the equivalent of such stated means be employed.

I therefore particularly point out and distinctly claim as my invention:—

1. In apparatus for electrolyzing a fused salt bath, a closed sectional partition of refractory material to separate anode and cathode products comprising a plurality of generally plate-shaped members provided with means to suspend the same vertically from a support, and strut members disposed transversely between oppositely placed plate members.

2. In apparatus for electrolyzing a fused salt bath, a closed sectional partition of refractory material to separate anode and cathode products comprising a plurality of generally plate-shaped members provided with means to suspend the same vertically from a support, and strut members joining oppositely placed pairs of plate members, such strut members being formed integrally with at least one of each pair of plate members.

3. In apparatus for electrolyzing a fused salt bath, a closed sectional partition of refractory material to separate anode and cathode products comprising end members provided with a flange on the outer face to suspend the same vertically from a support and having at least two sides, such sides being disposed approximately at right angles to each other, similarly flanged plate-like intermediate members and strut members joining oppositely placed intermediate members.

4. In apparatus for electrolyzing a fused salt bath, a closed sectional partition of refractory material to separate anode and cathode products comprising end members

provided with a flange on the outer face to suspend the same vertically from a support and having at least two sides, such sides being disposed approximately at right angles to each other, similarly flanged plate-like intermediate members and strut members joining and formed integrally with at least one of each pair of oppositely placed intermediate members.

- 10 5. In apparatus for electrolyzing a fused salt bath, a closed sectional partition of refractory material to separate anode and cathode products comprising U-shaped end members provided with a flange on the outer face to suspend the same vertically from a support, similarly flanged plate-like intermediate members and strut members joining oppositely placed intermediate members.
- 15 6. In apparatus for electrolyzing a fused salt bath, a closed sectional partition of refractory material to separate anode and cathode products comprising U-shaped end members provided with a flange on the outer face to suspend the same vertically from a support, similarly flanged plate-like intermediate members and strut members joining and formed integrally with at least one of each pair of oppositely placed intermediate members.
- 20 7. In apparatus for electrolyzing a fused salt bath, a closed sectional partition of refractory material to separate anode and cathode products comprising two U-shaped end members provided with a flange on the outer face to suspend the same vertically from a support, and a plurality of H-shaped intermediate members consisting of two opposed similarly flanged plate-like sections joined by a strut section.

40 Signed by me this 26 day of July, 1929.
LOUIS E. WARD.
